ALBERT A. DAVIS AND BENJAMIN F. WALKER, OF LOWELL, MASSACHUSETTS, ASSIGNEES TO B. F. WALKER AND M. R. FAVOR.

Letters Patent No. 92,586, dated July 13, 1869.

IMPROVEMENT IN LUBRICATING-DEVICE FOR SPINDLES.

The Schedule referred to in these Letters Patent and making part of the same.

To all whom it may concern:

Be it known that we, ALBERT A. DAVIS and BENJAMIN F. WALKER, both of Lowell, in the county of Middlesex, and State of Massachusetts, have invented certain new and useful Improvements in the Device or Apparatus which is Used for Oiling or Lubricating the Spindles of Speeders, Stretchers, Slubbers, and other roving-frames, of which the following is a full, clear, and exact description, reference being had to the accompanying drawings, making part of this specification, in which—

Figure 1 is a vertical central section of a speeder-spindle, and the principal supporting parts in which the spindle operates, with our invention applied thereto.

Figure 2 is a side elevation, and

Figure 3, a top view of one of our improved lubricators detached.

Our invention consists in the employment of a separate lubricating-device for each spindle of the slubber or other roving-frame, said lubricator being an independent as well as a separate device, and has no other function or operation, except to oil or lubricate the spindle.

This invention has for its object to economize (in the use of oil or other lubricant) in time required for applying the lubricating-substance to the spindles, and in the more certain and uniform lubricating-action of the lubricating-material.

In oiling the spindles of slubbers and other roving-frames, the oil is usually applied to the spindle above the top gear, and is allowed to run down between *g* and *h*, *g* representing the hub of the top gear, as seen in fig. 1.

The oiling-operation is usually performed about four times each day, and can be performed only when the operating parts of the frame are at rest, and when the bobbins are being doffed.

To greatly economize in the use of the oil or other lubricating-substances on the spindles of roving-frames, and to save time, and lubricate such spindles with uniformity and certainty, we apply to each of these spindles a separate and independent oiling-device, which surrounds the spindle, and whether the spindle moves up and down in the frame, or the frame moves on the spindle, our oiling-device may be secured to some part of the frame, or to the top rail *B*, and then the spindle may move in and through the oiling-device, or the oiling-device may move on the spindle with the moving part of the frame.

This oiling-device consists of a cup or tube, *C*, having a bottom, *D*, and a tubular projection, *E*, which fits the spindle.

An arm, *F*, is fastened to the side of the cup *C*, and extends onward or outward and upward, to connect with some part of the frame, and hold the oiling-device in its place on the spindle.

Within the cup *C*, and surrounding the spindle, in contact with its outer surface, is an absorbent, *G*, which may be felted washers, or sponge, or any fibrous substance that will absorb and properly retain oil and deliver it to the spindle.

On the top of the absorbent, within the cup, and surrounding the spindle *H*, we apply a metal or other washer, *d*, of sufficient weight or specific gravity to press on the absorbent, and gradually work the oil out of the latter on to the spindle, and also prevent the absorbent being carried upward by the downward motion or movement of the spindle when in operation.

In order to apply our oiling-device, the spindle is raised or drawn upward, the lower end to near the under side of the top rail *B*, when the oiling-device is slid on to the spindle, and the latter is allowed to move downward to its proper position, with the lower end in the step *I*.

The oiling-device, is then fastened to some suitable support, and adjusted for the free action of the spindle through the same.

The absorbent is saturated with lubricating-substance, either before or after being applied to the spindle, and if after being applied, such lubricating-substance is applied at and through an annular space, *c*, between the spindle and the washer *d*.

After our improvement has been applied to the spindles of a roving-frame, all such spindles are oiled, as last described, and without stopping the frame.

We have found by experiment that, instead of oiling the spindles of a slubber or a speeder so frequently, by the use of our improvement such spindles are well and uniformly oiled by filling or charging the absorbent with oil once in about seven days, considerable saving of time is effected, and an immense saving in oil or lubricating-material.

What we claim as our invention, and desire to secure by Letters Patent, is—

A separate and independent oiling-device with each spindle of a speeder or other roving-frame, when constructed and arranged to operate as and for the purpose specified.

ALBERT A. DAVIS.
BENJAMIN F. WALKER.
